(57) **CLAIM**

The ornamental design for a seat for baby carriages, as shown and described.

DESCRIPTION

1. Seat for baby carriages
- 1.1 is a top, front, and right side perspective view of a seat for baby carriages showing my new design;
- 1.2 is a top, rear, and right side perspective view thereof;
- 1.3 is a rear elevation view thereof;
- 1.4 is a right side elevation view thereof;
- 1.5 is a right side elevation view thereof, wherein the seat is shown in a fully reclined position;
- 1.6 is a rear and left side view thereof, wherein the seat is shown in a collapsed position;
- 1.7 is a front and left side perspective view thereof, wherein the seat is shown in a collapsed position; and
- 1.8 is a top, front, and right side perspective view thereof, wherein the seat is shown installed in an exemplary baby carriage.

The broken line showing of a baby carriage is provided for the purpose of illustrating environmental structure, of which forms no part of the claimed design.
